UNITED STATES PATENT OFFICE.

CHARLES J. REED, OF GLENSIDE, PENNSYLVANIA.

SPARK-GAP MECHANISM.

1,309,913.

Specification of Letters Patent. Patented July 15, 1919.

Application filed August 8, 1917. Serial No. 185,113.

To all whom it may concern:

Be it known that I, CHARLES J. REED, a citizen of the United States, residing at Glenside, in the county of Montgomery and State of Pennsylvania, have invented certain new and useful Improvements in Spark-Gap Mechanisms, of which the following is a specification.

My invention relates to improvements in spark-gap mechanisms in which electrical contact is completed through a conducting arm or support removably attached at one end to an igniting mechanism and at the other end at right angle to a tube or chamber comprising the spark gap of a high tension electric circuit.

The object of my invention is the provision of a device for the purpose indicated which is extremely simple and compact and occupies little space.

For a fuller understanding of my invention, reference is had to the appended drawings in which:—

Figure 1 is a perspective view of my invention as applied to an igniter and a high-tension spark gap;

Figs. 2 and 3 are plan view and vertical section respectively of one form of my invention; and

Figs. 4 and 5 plan view and vertical section respectively of a modified form.

In the drawings, 1 represents the conducting wire leading from an igniter to a binding post consisting of the usual stud 2 and clamping nut 3. 4 represents a fixed spark-gap chamber and 5 and 6 a binding post and clamping nut thereon, respectively.

The spark-gap mechanism forming my invention comprises a body 7 of fiber or any other suitable insulating material and two electrical conductors 8 and 9, located on opposite sides of the body 7 and carrying the spark points.

The conductors 8 and 9 are preferably made of flat strips of material and may be attached to the support 7 in any suitable way, as by rivets or pins 18. At the other end, which is preferably widened, the metal is pressed out of the plane of the strip to provide cone shaped projections 10 and 11 terminating in apexes 12 and 13. The body 7 has an aperture 14 of such size as to receive the cone shaped projections 10 and 11. The apexes 12 and 13 are directly opposite one another and form the spark points. The

body 7 has a perforation 15, at one end in registration with a perforation 16 in plate 9 so that the device may be attached to the stud 5 and clamped by nut 6 to the chamber 4. The conducting wire 1 may be provided with a perforated lug 17 adapted to be attached to stud 2 and clamped to the conductor 8 by clamping nut 3.

Instead of making the conductors 8 and 9 and the projections 10 and 11 of one piece, I may advantageously form the cone shaped elements separately. As shown in Figs. 4 and 5, the elements 20 and 21 are made in the form of disks and shaped by suitable dies to assume the form of cone shaped projections. This modification has the advantage that the projections may be made of nickel or other suitable material offering a comparatively high resistance against deterioration by the arc without materially increasing the cost of the device. In order to hold the projections 20 and 21 securely in position, I preferably ream out the aperture 14 at both ends or form recesses in some other suitable manner to receive the projections. Spring arms 22 and 23 of cheaper material, such as brass, are attached to the body 7 as in the device shown in Figs. 2 and 3 and bear at the other end on the projections 20 and 21 to hold them in place and make good electrical contact therewith.

As shown in this form of device, the support 7 may receive depressions 24 and 25 at opposite ends to reduce the height of the clamping mechanism to a minimum, to avoid projecting parts as much as possible and to make the device as a whole of thin construction.

While I have shown in the drawing only the preferred form with the conductors extending in opposite directions, I conceive that the same purpose could be accomplished by having the conductors extend at right angles to each other or some other angle instead of in opposite directions.

It is also understood that instead of having two spark points, one on each conductor, a single spark point could be employed and the opposing conductor could be flat.

The characteristic features of my invention may be given form in various other ways and what is shown, is merely for purposes of illustration.

By the expression "sparking relation" in the claims, I mean to convey the idea that a

spark point may be provided on one or both conductors or disks in the aperture 14.

What I claim is:—

- 5 1. A spark-gap mechanism comprising a body of insulating material having an aperture, and electric conductors extending into said aperture from opposite ends thereof to form a spark gap.
- 10 2. A spark-gap mechanism comprising a flat support having an aperture, electric conductors on opposite sides of the support formed of flat stock, and means for electrically insulating said conductors from each other, said conductors being so formed relatively to each other as to establish a sparking relation in said aperture.
- 15 3. A spark-gap mechanism comprising a flat elongated support having an aperture, electric conductors on opposite sides of the support formed of flat stock, and means for electrically insulating said conductors from each other, said conductors being so formed relatively to each other as to establish a sparking relation in said aperture.
- 20 4. A spark-gap mechanism comprising a flat elongated support of insulating material having an aperture, and electric conductors on opposite sides of the support formed of flat stock and having portions in
- 25 said aperture in sparking relation.
- 30 5. A spark-gap mechanism comprising a support having an aperture, electric conductors on opposite sides of said support and across the aperture, one of said conductors having a cone-shaped projection extending into said aperture and means for electrically insulating said conductors from each other.
- 35 6. A spark-gap mechanism comprising a support of insulating material having an aperture and electric conductors on opposite sides of said support and across the aperture at the ends thereof, one of said conductors having a cone-shaped projection extending
- 40 into said aperture.
- 45 7. A spark-gap mechanism comprising a flat support of insulating material having an aperture and electric conductors on opposite sides of said support, one of said conductors having a cone-shaped projection extending into said aperture.
- 50 8. A spark-gap mechanism comprising a flat elongated support of insulating material having an aperture and electric conductors on opposite sides of said support, one of said conductors having a cone-shaped projection extending into said aperture.
- 55 9. A spark-gap mechanism comprising a flat elongated support of insulating material having an aperture and electric conductors of flat stock on opposite sides of said support, one of said conductors having a cone-shaped projection extending into the said aperture.
- 60 10. A spark-gap mechanism comprising a support having an aperture, electrical conductors on opposite sides of said support and across the aperture, each of said conductors having a cone-shaped projection extending into said aperture and means for electrically insulating said conductors from each other.
- 65 11. A spark-gap mechanism comprising a support having an aperture, a metallic disk at each end of the aperture, said disks having portions opposite each other in sparking relation, electric conductors engaging said disk, the disk and its conductor on one side being electrically insulated from the disk and its conductor on the opposite side.
- 70 12. A spark-gap mechanism comprising a support having an aperture, a metallic disk at each end of said aperture, a spark point on one of said disks and electric conductors engaging said disks, the disk and its conductor on one side being electrically insulated from the disk and its conductor on the opposite side.
- 75 13. A spark-gap mechanism comprising a support of insulating material having an aperture, a metallic disk at each end of said aperture, a spark point on one of said disks and electric conductors engaging said disks.
- 80 14. A spark-gap mechanism comprising a support of insulating material having an aperture, a metallic disk seated in each end of said aperture, a spark point on one of said disks and electric conductors engaging said disks.
- 85 15. A spark-gap mechanism comprising a support of insulating material having an aperture, a metallic disk at each end of said aperture, a spark point on one of said disks and means for holding said disks in said aperture and making electrical contact therewith.
- 90 16. A spark-gap mechanism comprising a support of insulating material having an aperture, a metallic disk at each end of said aperture, a spark point on one of said disks and an electric conductor to hold each disk in position and carry current thereto.
- 95 17. A spark-gap mechanism comprising a support of insulating material having an aperture, a metallic disk at each end of metal having a high resistance against deterioration by sparking, a spark point on one of said disks and an electric conductor to hold each disk in position and carry current thereto.
- 100 18. A spark-gap mechanism comprising a support of insulating material having an aperture, a metallic disk at each end of metal having a high resistance against deterioration by sparking, a spark point on each disk, and an electric conductor to hold each disk in position and carrying current thereto.
- 105 19. A spark-gap mechanism comprising a support of insulating material having an

aperture, conductors of flat stock on opposite sides of said support across the aperture and extending in different directions, a spark point on each conductor projecting into the 5 said aperture and means on each conductor for making an electrical connection to an electrical device.

20. A spark-gap mechanism comprising a support of insulating material having an 10 aperture, conductors of flat stock on opposite sides of said support and extending in different directions, one end of each conductor terminating in a disk adapted to close the aperture and carrying a spark point 15 projecting into said aperture and the other

end of each conductor affording means for electrical connection to an electrical device.

21. A spark-gap mechanism comprising a support of insulating material having an aperture, a metallic disk seated in each end 20 of said aperture, metallic spring means on opposite sides of said support and extending in different directions, each of said spring means acting at one end upon one of said disks to retain it in place and means at the 25 other end thereof for affording an electric connection to an electrical device.

In testimony whereof, I affix my signature.

CHARLES J. REED.
